PARTITION

Seymour Rutkin, 445 E. 65th St., New York, N.Y.

Filed May 26, 1958, Ser. No. 51,077

Term of patent 3½ years

(Cl. D13—1)

FIG. 3

FIG. 2

The rear of the partition in each embodiment is a mirror image of the front shown.

I claim:

The ornamental design for a partition, substantially as shown and described.
